UNITED STATES PATENT OFFICE

162,735

REMOVABLE LAMP SHADE COVER

Margot Hunziker, New York, N. Y.

Application November 29, 1950, Serial No. 13,180

Term of patent 3½ years

(Cl. D48—16)

To all whom it may concern:

Be it known that I, Margot Hunziker, a citizen of the United States of America, residing in New York, county of New York, and State of New York, have invented a new, original, and ornamental Design for a Removable Lamp Shade Cover, of which the following is a specification, reference being had to the accompanying drawing, forming part thereof.

The single drawing figure is a surface view of a removable lamp shade cover showing my new design, the back thereof being plain.

The portions shown in broken lines are identical with the lower half shown in solid lines.

The nature of the object is substantially thin and flat.

I claim:

The ornamental design for a removable lamp shade cover, substantially as shown and described.

MARGOT HUNZIKER.
